DESIGN FOR A COMBINED WINDOW VENTILATING FAN GUARD AND MOUNTING THEREFOR

William J. Campbell, Indianapolis, Ind., assignor to Climax Machinery Company, Indianapolis, Ind., a corporation of Indiana

Application November 25, 1940, Serial No. 96,787

Term of patent 7 years

To all whom it may concern:

Be it known that I, William J. Campbell, a citizen of the United States, residing at Indianapolis, in the county of Marion and State of Indiana, have invented a new, original, and ornamental Design for a Combined Window Ventilating Fan Guard and Mounting Therefor, of which the following is a specification; reference being had to the accompanying drawing, forming a part thereof.

In the drawing:

Fig. 1 is a rear elevational view of a combined window ventilating fan guard and mounting therefor, showing my new design; and

Fig. 2 is a side elevational view thereof.

The dominant features of my design are illustrated in solid lines.

I claim:

The ornamental design for a combined window ventilating fan guard and mounting therefor, as shown and described.

WILLIAM J. CAMPBELL.
